[57] CLAIM

The ornamental design for a shoe, as shown and described.

DESCRIPTION

FIG. 1 is a front elevational view of a shoe showing my new design;

FIG. 2 is a rear elevational view thereof;

FIG. 3 is a top plan view thereof;

FIG. 4 is a bottom view thereof;

FIG. 5 is a left side elevational view thereof; and
FIG. 6 is a right side elevational view thereof.

The shoe shown in the figures is for use on the right foot, the shoe for use on the left foot being identical but a mirror image thereof.
